UNITED STATES PATENT OFFICE.

ALLAN J. CLINE, OF CHICAGO, ILLINOIS.

MOTOR-CONTROLLER.

1,274,684.

Specification of Letters Patent.

Patented Aug. 6, 1918.

Application filed May 22, 1915. Serial No. 29,763.

To all whom it may concern:

Be it known that I, ALLAN J. CLINE, a citizen of the United States, and a resident of Chicago, county of Cook, and State of Illinois, have invented certain new and useful Improvements in Motor-Controllers, of which the following is a specification.

The invention relates to controllers for electric motors that are employed for operating printing presses, machine tools and the like, at different speeds, and seeks to provide an improved means comprising a manually operable switch by which the operator of the press or other machine has full control of the different motor speeds, in combination with automatically operating devices which protect the motor and automatically control its acceleration in accordance with the setting of the manually operable switch. A further object of the invention is to provide an arrangement in which the main parts which control the armature circuit can be located at one station at a distance from the main controlling station or switch and in which it is only necessary to connect small, light wires to the controlling switch so that the latter may be conveniently mounted on the machine within easy reach of the operator.

The invention consists in the features of improvement hereinafter set forth, illustrated in the accompanying drawing and more particularly pointed out in the appended claims.

In the accompanying drawing, the invention is illustrated in its preferred arrangement.

The conductors 10 and 11 of the supply circuit for the motor 12, are connected to the mains 13 by a knife switch 14 in the usual manner. The controlling devices are preferably located at two stations, the manually operable or main controlling switch being located at a station A and the parts which, under control of the switch, govern the acceleration of the motor, being located at another station, B.

The station A comprises a swinging, manually operable switch arm 15 and a set of cooperating contact bars 16, 17, 18, 19 and 20 mounted on a suitable support 21. The switch arm is arranged to move between a pair of stops 22 and 23 over the contact bars and over the contacts of a variable field resistance 24 which is connected to the contact bar 16. The parts are so arranged

that, as the switch arm moves from its open position in engagement with the stop 22, it initially engages the contact bars 16 and 17, and thereafter successively engages the contact bars 18, 19 and 20. The switch arm remains in engagement with the contact bars 17, 18, 19 and 20 until its movement is arrested by the stop 23, but between the ends of its movement it is disengaged from the contact bar 16 and thereafter successively engages the contacts of the variable field resistance 24.

Station B comprises a main resistance 25 for the motor circuit and a set of electro-magnetic switches 26, 27 and 28, which are arranged to cut out successive portions of the main resistance 25. An electro-magnetic starting switch 29 is also preferably located at station B, and an electro-magnetic switch 30 is arranged at station B for short-circuiting the field resistance 24.

The conductor 10 of the supply circuit is connected to one of the motor terminals, the other motor terminal being connected to one of the terminals of the resistance 25. The other resistance terminal and the main supply conductor 11 are connected to the contacts of the starting switch 29. The motor may be either shunt or compound wound. In the arrangement shown, the field 31 is arranged to be connected to the supply conductor 10 by the switch arm 15 and contact bar 16, and to the supply conductor 11 by the contacts of the starting switch 29. The coil of the starting switch is interposed between the supply conductor 11 and the contact bar 17, and the switch arm 15 is connected to the supply conductor 10.

The coils of the resistance switches 26, 27 and 28 are interposed in branch circuits between the negative pole of the motor and the positive supply conductor 10 and these branch circuits are arranged to be successively closed as the controlling switch arm 15 engages the contact bars 18, 19 and 20. The coils of these resistance switches are thus energized by the counter electromotive force developed by the motor, and the windings are such that, when in circuit, these coils will operate their contacts successively, to thereby reduce the resistance of the motor circuit, as the motor accelerates and reaches different predetermined speeds and thereby develops a counter electromotive force of different predetermined amounts.

Thus, while the operator by means of the controlling switch 15 can quickly close the operating circuits of one or more of the resistance switches, the switches will not operate until the speed of the motor has increased sufficiently to develop the requisite counter electromotive force. Although the operator may set the switch arm in accordance with the desired speed, the resistance switches will automatically protect the motor and prevent sudden rushes of current therethrough.

The arrangement is preferably such that, when the controlling switch arm 15 is engaged with the contact bar 20 to thereby close the operating circuit of the resistance switch 28, the motor will operate at normal speed. If it is desired to further accelerate the motor, the switch arm may be moved over the contacts of the field resistance to thereby cut down the current passing through the motor field and so increase the speed of the motor. When this occurs, the resistance switch 28 has been operated and the coil of the switch 30 is connected in series with the armature of the motor. The winding of this coil is such that, if the field resistance 24 is thrown into the circuit too quickly and causes a rush of current through the motor armature, the contacts of the switch 30 will close a short circuit around the field resistance and thereby check the rush of current through the motor armature and reduce its speed. The contacts of switch 30 will then open and, if another rush of current passes through the armature will again close. In this way, the contacts of the switch 30 will open and close, or "flutter", as it is termed, until the motor reaches a definite predetermined speed in accordance with the setting of the controlling switch arm 15.

In operation, the different circuits can be traced as follows. When the controlling switch arm is moved from initial position, it first engages the contact bars 16 and 17 to close the operating circuit of the starting switch 29, as follows: from main conductor 10, by conductor 32, switch arm 15, contact bar 17, conductor 33, coil of switch 29, and conductor 34 to main conductor 11. The contacts of switch 29 are then engaged and the main supply circuit is closed from conductor 10 through the armature of the motor, conductor 35, armature resistance 25, conductor 36, and contacts of switch 29 to main conductor 11. The field circuit is also closed from main conductor 10 by conductor 32, switch arm 15, contact bar 16, conductor 37, through the field and by conductors 38 and 36 and contacts of switch 29 to the main conductor 11. The motor will then operate at slow speed, the entire resistance 25 being interposed in the armature circuit.

The coils of the resistance switches 26, 27 and 28 are connected to the negative termin-

nal of the motor by a conductor 39, and to the contact bars 18, 19 and 20 by branch conductors 40. One of the contacts of each of the switches 26, 27 and 28 is connected to the negative terminal of the motor by conductors 35 and 41. The other contacts of switches 26 and 27 are connected by conductors 42 to intermediate points of the armature resistance 25 and the other contact of the switch 28 is connected by a conductor 43 to the conductor 36. The operation of the resistance switches will of course cut out successive portions of the resistance from the armature circuit. If the switch arm is moved onto contact bar 18, for example, the circuit is closed from the negative pole of the motor by conductors 35 and 39, coil of switch 26, one of the conductors 40, contact bar 18, switch arm 15 and conductor 32 to the positive main conductor 10. If the motor has been running for some appreciable time at slow speed, sufficient counter electromotive force will be developed thereby to energize the coil of switch 26 and thereby close its contacts to cut out a portion of the resistance 25, and thereby effect an increase in speed of the motor. But if the switch arm 15 is quickly shifted from its open position into engagement with the contact bar 18, while the circuit of coil 26 is closed, it will not operate at once, but its contacts will remain open to maintain the entire resistance 25 in the motor circuit until the motor has reached a certain predetermined speed and developed a counter electromotive force of sufficient predetermined amount. The resistance switches 27 and 28, under control of the switch arm 15 and contact bars 19 and 20, operate in a similar manner, except that a greater electromotive force is required to operate switch 27 and a still greater to operate switch 28. Hence the motor must proportionately increase its speed to effect the operation of these switches and the cutting out of the sections of the resistance 25 controlled thereby. It is obvious that in case the operator quickly shifts the switch arm 15 from open position into engagement with the contact bar 20, that the resistance switches 26, 27 and 28 will not operate at once, but will successively operate as the speed of the motor gradually increases to cut out successive portions of the resistance.

Preferably, as stated, the motor is arranged to run at normal speed when the resistance switch 28 is operated. It should be noted that the coil of switch 30 is interposed in the conductor 43 and that, when the contacts of switch 28 are closed, and the motor is running at normal speed, this coil is in series with the armature of the motor. If a further increase of speed is required, the switch arm is moved over one or more of the contacts of the field resistance 24. If the switch arm is thus moved quickly and

- starting switch and the field circuit of the motor, and thereafter successively close the operating circuits of said resistance switches and engage the contacts of said variable 5 field resistance to accelerate the motor, and an automatic electro-magnetic switch having its coil in series with the armature for short-circuiting said field resistance until the motor reaches a predetermined speed in accordance with the setting of said switch arm. 10
8. In a controlling system for electric motors, the combination of a main station comprising an electro-magnetic starting switch for closing the armature circuit, a 15 variable armature resistance, and a series of electro-magnetic resistance switches arranged to cut out successive portions of said armature resistance as different predetermined electrical conditions are established in the 20 armature circuit, and a controlling station comprising a manually operable switch arm, coöperating contact bars and a variable field resistance, said switch-arm being arranged to initially close the field circuit and the operating 25 circuit of said starting switch and thereafter successively close the operating circuits of said resistance switches and engage the contacts of said field resistance, and a fluttering switch at the main station responsive to fluctuations of current in the armature 30 circuit and controlling a short circuit around said field resistance.
9. In a controller for electric motors, the combination with a motor, a supply circuit 35 and a resistance, of a resistance switch, an operating electromagnet therefor, and a manually operable controlling switch arranged to initially close the circuit through said motor and said resistance and thereafter close the circuit of said magnet and, in 40 reverse order, to successively open said circuits, said magnet being responsive to the
- counter-electromotive force developed by the motor and arranged to automatically operate said switch as the motor reaches a certain predetermined speed. 45
10. In a controller for electric motors, the combination with a motor, and a supply circuit therefor, of resistances in the armature and field circuits of said motor, an electro-magnetic switch responsive to the counter-electromotive force developed by the motor and, arranged to automatically cut out said armature resistance as the motor reaches a certain predetermined speed, and a manually operable controlling switch arranged to successively close the supply circuit of said motor and the operating circuit of said electromagnetic switch to successively increase the motor speed and thereafter coöperate 50 with said field resistance to further accelerate the motor, said switch being arranged to coöperate with said field resistance and open said circuits in reverse order to successively decrease the motor speed. 55
11. In a controller for electric motors, the combination of a motor and its supply circuit, of resistances in the armature and field circuits, respectively, of said motor, an electromagnetic switch arranged to automatically 60 cut out said armature resistance as the motor reaches a certain predetermined speed, a manually operable controlling switch arranged to successively close the supply circuit of said motor and the operating circuit 65 of said electromagnetic switch and thereafter coöperate with said field resistance to accelerate the motor, and an automatic electromagnetic switch responsive to fluctuations of current through the armature circuit 70 for intermittently short circuiting said field resistance until the motor reaches a predetermined speed. 75
